H. A. HABICHT.
DEVICE FOR DRILLING AND ENLARGING HOLES.
APPLICATION FILED JULY 26, 1920.

Patented Oct. 31, 1922.

Henry A. Habicht,
Frank W. Werner,
ATTORNEY

UNITED STATES PATENT OFFICE.

HENRY A. HABICHT, OF INDIANAPOLIS, INDIANA.

DEVICE FOR DRILLING AND ENLARGING HOLES.

Application filed July 26, 1920. Serial No. 399,048.

To all whom it may concern:

Be it known that I, HENRY A. HABICHT, a citizen of the United States, residing at Indianapolis, in the county of Marion and State 5 of Indiana, have invented certain new and useful Improvements in Devices for Drilling and Enlarging Holes, of which the following is a specification.

This invention relates to a device for 10 drilling and enlarging holes in metal boxes, being particularly adapted for use in the drilling of new holes or the reaming and enlarging of existing holes in metal boxes employed for enclosing the terminal ends of 15 metal conduits which encase electric wires for lighting purposes, in both public and private buildings.

In conforming to certain special and specific municipal ordinances for the prevention of fire, it is customary to install a metal 20 box as a part of the electrical equipment for enclosing the ends of the metal conduits enclosing the conductor wires. These boxes are provided with doors to render the interior accessible; are rather shallow compared 25 with their widths, and are usually located in out of the way places—on basement walls, storage rooms, etc.,—where repairs are made with difficulty and requiring considerable 30 labor and time. Moreover, it frequently happens in public buildings and similar places, that the original plans and specifications for the lighting systems prove inadequate or insufficient, or, as generally occurs, 35 additional lamps are added to the circuits from time to time until the capacity of the conductor wires is inadequate to carry the load, so that larger or a greater number of wires must be added, and incidentally necessitates larger conduits for enclosing the 40 wires. The above mentioned changes require either an increase in the number of openings in the terminal box or the enlarging of existing openings in the box. In 45 either case, this work is generally performed with an ordinary carpenter's brace and a reamer, and in view of the shallow character of the box and the proximity of the surface of the wall the movement of the reamer is restricted from a full rotation to a limited oscillatory movement, so that this class 50 of work in the art is characterized as being tedious, difficult, and one requiring much time.

One of the objects of the present invention is to obviate the above enumerated difficul-

ties by the provision of a device whereby a new hole may be easily drilled or an existing hole readily enlarged, with precision, speed and economy. 60

A further object of the invention consists in the provision of a device of the above character whereby holes of different diameters may be drilled without interchanging the parts. 65

I accomplish the above objects of the invention, and such others as may appear from a perusal of the following description and claims, by means of the construction illustrated in the accompanying drawings, 70 forming a part hereof, in which—

Figure 1 is a top or plan view of my improved hole drilling and enlarging device. Fig. 2 is a view partly in vertical section and partly in side elevation of the device. 75 Fig. 3 is a fragmentary detail view in front elevation of the chuck-head. Fig. 4 is a plan view of the face of the chuck-head. Fig. 4^a is a fragmentary detail plan view of one of the sliding boxes for supporting the tool 80 holders, showing the means for adjusting same. Fig. 5 is a horizontal view, partly in section and partly in elevation, on the line 5—5 in Fig. 2. Fig. 6 is a perspective view of one of the tool holders for the mounting 85 of the cutting tools. Fig. 7 is a perspective view of one of the adjustable sliding boxes for the mounting of the tool holders. Fig. 8 is a fragmentary detail view in side elevation 90 of the chuck-head, showing the device set or arranged for enlarging an existing hole.

Referring to the drawings, the body of the device comprises a metal frame 10, which is formed U-shaped and terminating in the 95 arms A and B which support the rotating parts of the device. The peculiar shape of frame 10 is such that its free ends may readily be inserted into the ordinary form of a metal box 11 forming the enclosure for 100 the terminal ends of the conduits for enclosing electric wires.

Passing transversely through arm A is a revoluble shaft 15 having a squared end 16 so that said shaft may be rotated by 105 means of an ordinary wrench. The lower portion of shaft 15 has its diameter slightly reduced to form a shoulder 17 and said shaft immediately below shoulder 17 is provided with threads to receive a threaded ring 18 110 which is adjusted on shaft 15 to abut and lock against shoulder 17, whereby shaft 15

is held against longitudinal travel in one direction, and shaft 15 is prevented from moving longitudinally in the opposite direction by means of a nut 19. 20 represents a chuck-head for the mounting and adjusting of the cutter blades. Head 20 is provided with a central aperture to receive the reduced spindle-end of shaft 15, and the enforced movement of rotation of head 20 is effected by means of a feather 21 which is arranged in a key-way 22 in shaft 15. The upper end of head 20 is reduced in diameter and is provided with threads which are adapted to engage corresponding threads in the internal wall of a collar 23. Collar 23 may freely rotate with head 20 but the collar is held against longitudinal movement through its engagement with a channel 24 which is formed by reducing the diameter of the lower end of threaded ring 18 and a shoulder formed by a disk-ring 25 which is secured to the lower face of ring 18 by means of the screws 26. The above construction contemplates that when shaft 15 is rotated a corresponding movement is imparted to chuck-head 20. Head 20 provides the means for slidably mounting the cutter blades for the drilling of new holes or the enlarging of existing holes, in the heretofore mentioned metal boxes. To accomplish the above purposes, head 20, as shown in Fig. 4, is provided in its face with a T-shaped slot 30 which is adapted to receive a pair of radially adjustable boxes 31 (Fig. 7) which provide the means for mounting and adjusting of the tool holders 32 radially of the axis of head 20. As stated, sliding boxes 31 are susceptible of radial adjustment in head 20 so that the distance of the cutter blades may be increased and decreased from the axis of the head 20 to enable holes of different diameters to be drilled, and sliding boxes 31 may be secured at any point along slot 30 by means of the set-screws 34. Each sliding box 31 is provided with a T-shaped channel 35 which is adapted to receive and guide one of the tool holders 32. With the above construction, the cutter blades are arranged on opposite sides and at uniform distances from the center of chuck-head 20, which adjustment is secured by means of the sliding boxes 31, and any minute adjustments necessary to bring the cutter blades an exact uniform distance from the axis of head 20 is effected by the independent adjustment of the tool holders 32 by means of the adjusting screws 38. Screws 38 are threaded throughout their entire length and pass through threaded apertures in tool holders 32, and, as indicated in Fig. 4, the inner ends of screws 38 are each provided with an annular groove 39. The inner ends of screws 38 are inserted into suitable apertures in the rear walls of channels 35, and by means of pins 40 passing through the sliding boxes 31 and the annular grooves 39 the screws 38 are free to rotate but are prevented from moving longitudinally. Hence, when screws 38 are rotated tool holders 32 are moved either toward or away from the axis of head 20, depending upon the direction in which said screws are rotated. 41 represents the cutter blades which are formed out of especially hardened steel, and these blades are detachably secured in suitable notches in the rear faces of the tool holders 32 by means of the screws 44. By means of this construction the cutter blades 41 may easily be replaced when worn or broken, without the necessity of discarding any of the remaining parts of the device.

Examining Fig. 2, it will be observed that the device is usually arranged so that the arm A, containing the drilling mechanism, will be introduced into the interior of metal box 11. When properly adjusted for the drilling of a hole, the centering head 50, which is removably arranged in the lower end of shaft 15, rests upon the surface of either the horizontal or vertical walls of box 11. Arm B of the device carries a clamping-bolt 51 which is provided with peripheral threads which engage suitable threads in a threaded aperture in said arm. The lower end of clamping-bolt 51 is squared, as at 52, so that the removable head 53 may be set firmly against the external surface of box 11, whereby the metal to be removed in forming the proposed opening is firmly held during the cutting operation.

The device is also provided with automatic feed mechanism so that the cutter blades 41 are moved or advanced intermittently and accorded a predetermined amount of travel, which is sufficient to correspond with the cutting capacity of the cutter blades 41, in cutting and removing the material. As shown in Fig. 5, the automatic feed mechanism comprises a crescent shaped spring 60 which is pivoted at its center to the under side of arm A by means of a screw 61, and the free ends of the spring 60 are bent in reverse curves to form the projections 62 which project into the path traveled by a pair of pins 63 which are mounted upon the upper end of the collar 23. When shaft 15 is rotated collar 23 and chuck-head 20 rotate in unison until pins 63 contact projections 62 on spring 60 when further rotation of collar 23 is momentarily arrested—until the applied stress expands or forces apart the slowly expanding free ends of spring 60 a sufficient distance to permit the passage of pins 63, after which collar 23 is again free to rotate with head 20 until its movement is again arrested by the re-engagement of pins 63 with the curved projections 62 of spring 60. During the above

mentioned momentary pause of the internally threaded collar 23, the enforced continued rotation of head 20, by means of the feather 21, causes the latter to move 5 downwardly by reason of its threaded connection with collar 23, whereby cutter blades 41 are forced intermittently into the metal during the operation of cutting.

Figure 8 illustrates the device when adjusted for the enlarging of an existing hole in metal box 11. In this operation, usually on account of the diameter of the existing hole, I provide the spindle end of shaft 15 with a clamping head 51^a of sufficient diameter to 10 more than extend across the existing hole, so that a firm footing for said head is secured on the metal lying contiguously about the existing hole, as clearly shown in Fig. 8. It is also desirable in enlarging holes to provide 15 a firm footing for the metal box on its under side, and with this end in view I preferably employ a wooden block 70 which is interposed between the head of clamping bolt 51 and the adjacent surface of box 11, so that 20 an extended area of the surface of the box is firmly held during the cutting operation, and preventing thereby possible injury to 25 the cutter blades 41.

Having thus fully described my said invention, what I desire to secure by Letters Patent, is—

1. In combination in a machine for cutting holes, of a frame having a pair of parallel spaced arms, a revolute shaft projecting

transversely through one of said arms and 35 having its lower exposed portion reduced in diameter to provide a shoulder, a ring threaded on the reduced portion of the shaft and abutting the shoulder, an internally 40 threaded collar engaging at one end an annular groove in the ring, a removable tool holding head keyed on the shaft and having external threads to engage the internal threads of the collar, and a clamp-screw carried by the second arm of the frame for 45 impinging the material worked upon against the centering head of the revolute shaft.

2. A device of the character described, a rotary shaft, a head having independent longitudinal travel of the shaft but enforced 50 rotary movement with the latter, peripheral threads on one external end of the head, an internally threaded collar arranged on the rotary shaft, a pair of diametrically positioned pins arranged on the external surface 55 of the collar, and means comprising a U-shaped spring having an intermediate attachment to the frame with the free ends of the spring arranged to alternately engage the pins and temporarily arresting the 60 movement of the collar during each revolution of the rotary shaft.

In witness whereof, I have hereunto set my hand and seal at Indianapolis, Indiana, this 24th day of July, A. D., one thousand 65 nine hundred and twenty.

HENRY A. HABICHT. [L. S.]
